ELECTRICAL CONNECTER

William H. Frank, Detroit, Mich.

Application March 7, 1936, Serial No. 67,741

7 Claims. (Cl. 173—259)

This application relates to electrical connectors and more particularly to connectors in the nature of clamps for electrical conductor terminals, such as those of cartridge fuses of the blade type.

5 The principal object of the present invention is to provide a connector which includes a stationary body and a clamping screw so positioned that when threaded home it will cause a surface of the terminal to move along and 10 against a surface of the connector body to produce a wiping contact between the surfaces and will clamp the terminal firmly in place and with good electrical contact in and to the body of the connector.

15 This application is a continuation in part of my prior application Serial No. 717,990, filed March 29, 1934.

Further objects of the invention will be readily apparent upon reference to the following detailed description of the embodiments shown in the appended drawing. In this drawing,

Fig. 1 is an elevation view of a connector arranged for clamping a blade terminal in place; Fig. 2 is a plan view thereof; 25 Fig. 3 is an end view of a modified form of connector for clamping a blade terminal in place; Fig. 4 is a fragmentary exploded view of the same.

Referring to the drawing it will be seen that 30 the connector of Figs. 1 and 2 comprises a stationary body 10 having walls 11, 12, and 14. The wall 12 has two tapped holes for the reception of screws 17 which secure the body to an insulation base 19 and thereby anchor the body 35 with respect to the base so that the parts which cooperate with the body may be manipulated to clamp a terminal in place in the connector.

For clamping a member 42, such as the blade end or terminal of a cartridge fuse or the like 40 to the body, and thereby electrically connecting it thereto, there is provided for cooperation with the outside surface 33 of the wall 11 an extension in the form of a rib or flange 61 providing a V-shaped groove or pocket 62 into which the 45 member 42 may be biased by washer head screws 63 threaded into tapped holes 64 of the body at the upper part of the latter. Tightening of the screws 63, which are at an acute angle to the surface 33, wedges the lower edge of blade 50 42 into pocket 62 and biases blade 42 along and against surface 33 to produce a wiping contact between the surface of the blade and the surface 33 of the body.

In Figs. 3 and 4 there is disclosed a modified 55 form of connector for a blade end of a cartridge fuse. In the modification of Figs. 3 and 4 the screw means comprises a screw 70 which threads into a tapped hole 70a whose axis is at an acute angle with respect to the surface 33 along and 60 against which is biased the blade, not indicated,

and the head of the screw is arranged to direct a clamping plate 71, whose edge 72 is hooked around the edge 73 of the connector to form a pivotal mounting for the clamping plate 71, into engagement with the upper edge of the blade 5 and cause the blade to be urged along and against the surface 33 and its lower edge to be directed into the pocket or groove 62 between the wall 33 and the flange 61 projecting from the wall 12 of the connector. A coned coil spring 74 is disposed between the upper surface of the wall 11 and the clamping plate 71 and is received within a crowned portion 75 of such clamping plate, and such spring, surrounding the screw 70, normally tends to raise the free edge of the clamping plate 71 clear of the connector 11 to permit facile association of a blade with the connector, whereupon tightening of the screw 70 is all that is necessary to clamp the blade tightly and firmly in place.

Now having described the connectors herein illustrated, reference will be had to the claims which follow for a determination of the monopoly sought to be covered herein.

I claim:

1. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the 30 connector and engages the aforesaid adjacent faces, and a screw threaded into the upper part of said wall at an obtuse angle to the terminal engaging flat face of the side wall so that its head causes the lower edge of the terminal to 35 be wedged into the pocket and the flat surface of the terminal to be biased along and against the terminal engaging flat face of the side wall and towards the pocket.

2. For use with a blade terminal, an electrical 45 connector comprising a body having a base engaging wall having a flange projecting upwardly therefrom and a flat face side wall also projecting upwardly therefrom, to a considerable extent, the adjacent faces of the base, the side 50 wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the terminal engaging flat face of the side wall so that its head causes the lower edge of the terminal to 55 be wedged into the pocket and the flat surface of the terminal to be biased along and against the terminal engaging flat face of the side wall and towards the pocket.

flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part.

3. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the terminal engaging flat face of the side wall so that its head causes the lower edge of the terminal to be wedged into the pocket and the flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part, by having an edge of itself hooked around an edge of such upper part.

4. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the terminal engaging flat face of the side wall so that its head causes the lower edge of the terminal to be wedged into the pocket and the flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part, by having an edge of itself hooked around an edge of such upper part, the screw passing through said plate, and resilient means normally tending to rock said plate on its pivotal mounting so that its free edge is considerably distant from the upper part of the connector.

5. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the

terminal engaging flat face of the side wall so that its head causes the lower edge of the terminal to be wedged into the pocket and the flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part, the screw passing through said plate, and resilient means normally tending to rock said plate on its pivotal mounting so that its free edge is considerably distant from the upper part of the connector.

6. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the terminal engaging flat face of the side wall so that its head causes the lower edge of the terminal to be wedged into the pocket and the flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part, the screw passing through said plate, and resilient means between the plate and the upper of the connector normally tending to rock said plate on its pivotal mounting so that its free edge is considerably distant from the upper part of the connector.

7. For use with a blade terminal, an electrical connector comprising a body having a base engaging wall having a flange projecting upwardly therefrom and a flat face side wall also projecting upwardly therefrom, to a considerable extent, the adjacent faces of the base, the side wall, and the flange being proportioned and arranged to form an externally exposed pocket of proper dimension to fit closely the edge of the blade terminal, when the latter is inserted within the connector and engages the aforesaid adjacent faces, and a screw threaded into the upper part of said wall at an obtuse angle to the terminal engaging flat face of the side wall so that its head causes the lower edge of the terminal to be wedged into the pocket and the flat surface of the terminal to be biased along and against the terminal engaging flat face of the side wall and towards the pocket, the connector having a clamping plate between the screw head and the upper part of the wall into which the screw is threaded, the clamping plate being pivotally mounted on such upper part, by having an edge of itself hooked around an edge of such upper part, the screw passing through said plate, and resilient means between the plate and the upper part of the connector normally tending to rock said plate on its pivotal mounting so that its free edge is considerably distant from the upper part of the connector.
